VACUUM DISTILLATION

Kenneth C. D. Hickman, Rochester, N. Y., assignor, by mesne assignments, to Distillation Products, Inc., Rochester, N. Y., a corporation of Delaware

Application January 28, 1938, Serial No. 187,454

5 Claims. (Cl. 202—205)

This invention relates to improved method and means for fractionating under high vacuum conditions and particularly high vacuum conditions wherein the evaporating and condensing surfaces 5 are separated by substantially unconstricted space.

It is known that the constituents of a mixture can be separated by high vacuum, short path or molecular distillation. Due to the fact that the 10 vapors must be immediately condensed, interchange of heat and constituents between vapor and condensate as ordinarily practiced is impossible. For this reason, no fractionation takes place and it has been calculated that the best degree of separation of constituents possible by 15 these types of distillation is about equal to one theoretical plate. In commercial practice, it is even less. This low capacity for separation is a decided shortcoming.

20 This invention has for its object to overcome the above difficulties of high vacuum, unconstricted path distillations. Another object is to provide means whereby improved fractionation or separation of constituents is possible under 25 high vacuum, short path or molecular distillation conditions. A further object is to provide short path, vacuum distillation apparatus which permits repeated redistillations without great loss of decomposable substances. Other objects will 30 become apparent from the following description.

In the following examples and description, I have set forth several of the preferred embodiments of my invention, but it is to be understood that they are given for the purposes of illustration and not as limitations thereof.

In the accompanying drawings, I have illustrated apparatus embodying the principles of my invention, wherein like numbers refer to like parts and wherein:

40 Fig. 1 is a horizontal section of a preferred type of fractionating still in which circulation of distillate over each vaporizing plate is caused by centrifugal force;

Fig. 2 is a detail of the scooping means shown 45 in Fig. 1 for removing liquid from the turned edge or surface of each of the rotating plates;

Fig. 3 is a detail drawing of the scraper or scoop device illustrated in Fig. 1 for removing liquid from the opposite surface of each of the 50 plates;

Fig. 4 is an elevation in section of a gravity still embodying the principles of my invention;

Fig. 5 illustrates in diagrammatic form an alternative type of gravity flow column;

55 Fig. 6 is a fragmentary section in elevation of

a modified method of disposing the centrifugal plates of the apparatus illustrated in Fig. 1;

Fig. 7 is a horizontal section of a centrifugal plate provided with an alternative method of removing liquid residues;

Fig. 8 is a fragmentary section in elevation of the device illustrated in Fig. 7;

Fig. 9 is a perspective view showing in detail the construction of the moving scraper of Fig. 7, and;

10 Figs. 10, 11 and 12 are diagrammatic sectional elevations illustrating alternative methods of collecting liquids from the surfaces of the centrifugal still plates.

15 Referring to Fig. 1, numeral 2 designates a cylindrical casing provided with end plates 3 and 4 and with conduit 5 which connects to high vacuum pumps (not shown). A shaft 6 is located in the center of the casing 2 and is housed at one end in bearing 7 and at the other by a packed bearing 8. The external end of the shaft extending through bearing 8 is provided with a drive pulley 9. Upon shaft 6 are rigidly mounted a plurality of spaced plates 10, 11, 12, 13, 14, 15, 16 and 17. Plates 10, 12, 14 and 16 are vaporizing 20 plates and are, therefore, provided with means for heating their surfaces, which comprises a heat radiating element 23 and a reflector 24. It will be noted that these vaporizing plates progressively decrease in area and, preferably, in a 25 geometric ratio for reasons which will be explained below. Plates 11, 13, 15 and 17 serve as condensing plates and are cooled by circulation of liquid over their top surfaces. It will be noted that each of the plates is provided with an inwardly turned edge. Cooling fluid originally introduced onto the center of the condensing plates is, when the shaft 6 is rotated, thrown into the gutter formed by the turned edge of each plate and is picked up by scoop 25. Due to the inertia 30 of the liquid and/or the action of pumps 18, it is caused to flow into conduit 26 through cooling coil 27 and back through conduit 28 to the center of the cooling plate. Substantially the same action takes place with each condensing plate. 35 These plates are also provided with removal devices 29, 30, 31 and 32 located at the periphery of their other or opposite surface, which serve to collect and remove liquid which is condensed upon the surface and is thrown to the periphery 40 by centrifugal force.

45 Each of the vaporizing plates 10, 12, 14 and 16 are provided with a scoop 33, 34, 35 and 36, respectively, which remove liquid from the turned edge gutter. Scoop 33 is connected to conduit 37 55

through which undistilled residue is withdrawn from the still. Scoop 34 connects to conduit 38 which is, in turn, connected to conduit 39 by which material to be distilled is introduced onto the center of heated plate 10. Scoop 29 connects to conduit 46 and scoop 35 of plate 14 connects to conduit 47. These conduits 46 and 47 joint to conduit 48 which serves to deliver liquid flowing therefrom onto the center of plate 12. Scoop 30 of condensing plate 13 is connected to conduit 49 and scoop 36 of vaporizing plate 16 is connected to conduit 50 and both of these conduits are connected to conduit 51 which serves to convey the liquid flowing therefrom onto the center surface of plate 14. Scoop 31 which removes liquid from the condensing surface 15 is connected to conduit 52 which serves to deliver the liquid onto the central surface of vaporizing plate 16. Scoop 32 is connected to conduit 53 by which the final fraction is removed from the still.

In Fig. 2 is illustrated the specific construction of the liquid removing scoop, such as 25, which removes liquid from the turned edge gutters of the condensing plates, such as plate 15. Numeral 25 designates the pointed scoop constructed from a small conduit, the point of which may be in close proximity to the surface of turned edge 62 or may actually touch it. The open part of the point faces in a direction opposite to that in which the plate is rotated and it is connected to a conduit 26 which serves to convey the removed liquid away from the scoop. The removing devices 33, 34, 35 and 36 are constructed in the same manner.

Referring to Fig. 3, which illustrates another specific method of removing liquid from the surfaces of the plates, and in particular condensate from a condensing plate such as 15, numeral 31 designates a rectangular hollow conduit which may lightly touch the surface of plate 15. The rectangular conduit is constricted at the closed end not in contact with the plate and is connected to a conduit 52 by which liquid forced into rectangular element 31 is conveyed away. The open end of the rectangular element faces in a direction opposite to that in which the plate is caused to rotate.

Referring to Fig. 4, numeral 80 designates a cylindrical still casing having a substantially greater length than diameter. It is provided with a flange 81 at the top and a gutter 82 and a withdrawal conduit 83 at its base. A second cylindrical element 84 slightly shorter and somewhat smaller in diameter is located inside the main casing 80 and concentric therewith. This central element is carried by an integral flange 85 which rests upon the packing or sealing material 86 placed upon flared edge 81 of element 80. Element 84 is divided into a plurality of zones 87, 88, 89 and 90, each of which can be maintained at a separate and distinct temperature by an electrical heating element located inside the cylinder (not shown). The boundaries of each of these zones is approximately indicated by the horizontal distributing devices 91, 92, 93 and 94 which may be made of gauze loosely attached to the surface of element 84 and which serve to evenly spread liquid over the heated surface in order to obtain a thin film for efficient vaporization. A series of annular gutters 100, 101, 102 are formed in the walls of the main still casing 80. Gutter 100 is approximately level with the bottom portion of zone 88, gutter 101 is approximately level with the bottom of zone 89 and gutter 102 is approximately level with the lowest portion of zone 90.

The annular space between the two main elements 80 and 84 is evacuated to the required degree by pumps, not shown, connected to conduit 103. Gutter 82 is connected to a conduit 104 which serves to convey liquid by means of pump 5 105 up onto the distributing element 92. Gutter 100 is connected to conduit 106 provided with pump 107 which serves to deliver liquid collecting therein up onto distributing device 93. Gutter 101 connects to conduit 108 provided with pump 109 which serves to deliver liquid collected therein onto distributing device 94. Gutter 102 is connected to conduit 110 through which the final fraction is withdrawn from the still. A conduit 111 serves to deliver the liquid to be distilled to 15 the distributing element 91.

Referring to Fig. 5, which is substantially the same as the apparatus of Fig. 4, except for the heating zones, numeral 80' designates a cylindrical still casing provided with evacuating conduit 20 103' and condensate collecting gutters 82', 100', 101' and 102'. Numerals 87', 88', 89' and 90' designate superimposed sections of a vaporizing column corresponding to sections 87, 88, 89 and 90 of Fig. 4.

Referring to Fig. 6, numerals 120 and 122 designate condenser plates, the upper and lower surfaces of which are provided with turned edges to form gutters 124, 126, 128 and 130. Numerals 132 and 134 designate evaporating surfaces provided 30 with gutters 136 and 138 respectively. Numeral 140 designates a branched conduit which serves to remove condensate from the gutters 124 and 126. Numeral 142 designates a branched conduit by which distilland is introduced onto and removed from evaporating plates 132 and 134. Numerals 146, 148, 150 and 152 designate conduits for introducing cooling fluid onto and removing it from condensing plates 120 and 122. Numeral 154 designates a radiant heater disposed between 40 evaporating plates 132 and 134.

Referring to Figs. 7, 8 and 9, numeral 160 designates a plurality of lugs integral with still casing 2 and 162 similar lugs supporting an adjustable gutter ring 164 which is in close proximity to the periphery of the centrifugal plate 166. The ring is split at 168 so that the clearance between it and the periphery of 45 166 can be adjusted. A conduit 170 communicates with the gutter. The center of plate 50 166 is raised at 172 and into the depression a stationary collar 171 is placed so as to leave a slight clearance at 174. The collar is shaped so as to form a reservoir 176 which communicates with conduit 178. Numeral 180 designates a cleft 55 scraper, the head of which is the same shape as the inside of the gutter ring 164 and the cleft portion of which extends over and into a slot formed in the periphery of plate 166.

Referring to Fig. 10, numeral 200 designates a 60 horizontal shaft to which is fixed a vertical vaporizing or condensing plate 202, the periphery of which extends into gutter 104 provided with inwardly turned edges 106.

Referring to Figs. 11 and 12, numeral 220 designates an approximately vertical shaft to which is fixed a plurality of plates 222 and 224, either or both of which may be condensing or vaporizing plates. Numeral 226 designates a gutter into which the periphery of plate 224 extends and 70 which is so constructed that the slit opening 228 is near the top portion thereof.

In operating the apparatus of Fig. 1, power is applied to pulley 9 and the shaft 6 and the various vaporizing and condensing plates are caused 75

to rotate at a fairly high speed. The vacuum pumps connected to conduit 5 are put into operation and cooling liquid which has a low vapor pressure such, for instance, as a low vapor pressure hydrocarbon or glyceride is introduced into the cooling coils 27 or onto the surface of the cooled condensing plates 11, 13, 15 and 17. During rotation, the cooling fluid flows through conduit 28 onto the center of each cooling plate. It is then caused to flow to the curved edge of that plate by centrifugal force. In passing over the surface of the plate, which is preferably of heat-conducting material, cooling of the plate takes place and the cooling liquid is warmed. This slightly warmed liquid is removed from the turned edge by scoop 25 and, due to the inertia of the liquid, and/or the action of pump 18, it is forced through the external cooling coils 27 and is returned to the center of the plate by way of conduit 28. Each of the condensing plates is, therefore, automatically cooled as long as the centrifugal elements are caused to rotate.

Liquid to be distilled and fractionated is introduced through conduit 39. The liquid flows to the center of vaporizing plate 10 and is thrown to the turned edge at the periphery thereof by centrifugal force while in the form of a thin film. A portion of the opposite surface of each of the condensing plates is exposed to the heat-radiating element 23, the heat of which is also reflected against the plate by reflector 24. As the plate rotates over this element, it is heated to distilling temperature, which may be regulated by the temperature of the element 23 and by the extent or area of the plate which is exposed to such radiation. In passing over the surface of plate 10 in the form of a thin film, vaporization of molecules in the high vacuum which exists throughout the system takes place. These molecules pass to the cool condensing surface 11 and are condensed thereon. The distance between the vaporizing and condensing surface is preferably small and under molecular conditions should be less than about the mean free path of the distilling molecules. Liquid condensed on the surface of plate 11 is thrown to the periphery where it is picked up by scoop 29. The force of gravity as well as the inertia of the liquid as it flows into this scoop causes it to continue to flow up through conduit 46 and into conduit 48 from which it is allowed to flow onto the center of vaporizing surface 12. This plate is preferably heated to a somewhat lower temperature than plate 10, the difference depending mainly upon the material distilled and the particular fraction removed. The liquid flowing from conduit 48 is caused to pass over the surface of vaporizing plate 12 and vaporized molecules are condensed upon the under surface of condensing plate 13. Undistilled residue from plate 12 is removed by scoop 34 and is forced by way of conduit 38 into conduit 39 where it is mixed with the initial material to be distilled. Condensate on plate 13 is thrown by centrifugal force into removing device 30 from which it is forced to flow through conduit 49 into conduit 51 which delivers it onto the center of vaporizing surface 14, which is heated to a somewhat lower temperature than plate 12. The liquid is thrown as a thin film over this surface and undistilled residue collects in the turned edge and is removed by a scoop 35 and delivered by way of conduit 47 into conduit 48 where it is mixed with the condensate removed from plate 11. Molecules vaporized from plate 14 condense upon the condensing plate 15 and are thrown by centrifugal

force to scoop 31 and flow thence into conduit 52 which delivers it onto the center surface of vaporizing plate 16, which is preferably at a temperature slightly lower than plate 14. On this plate, the final fraction vaporizes and is condensed upon plate 17 and is removed therefrom by scoop 32 and conduit 53. Undistilled residue collecting in the turned edge of plate 16 is removed by scoop 36 and flows through conduit 50 into conduit 51 where it is mixed with condensate removed from condensing plate 13.

The apparatus of Fig. 1 is simple to construct, but it has the disadvantage that considerable heat loss takes place, since the cool condensing surfaces are alternate to the heated evaporating surfaces. Fig. 6 illustrates the same apparatus, in which the plates having the same function are mounted in pairs so that these losses are reduced to one-half or less. Liquid to be distilled is introduced onto evaporating plates 132 and 134 by conduit 142. Heating of the plates is caused by 154. Undistilled residue is removed by conduit 144. Condensing plates 122 and 120 are cooled by fluid introduced thereon by conduits 146 and 148. Condensate is removed from both by conduit 140. The four plates effect a removal of 1 fraction of twice the volume of a pair of plates of Fig. 1. A fractionating still capable of removing several fractions is constructed by mounting several units identical to that of Fig. 5 on one 30 shaft and connecting them together as in Fig. 1.

The removal scoops shown in Figs. 2 and 3 can be used on either of the surfaces. In some cases small amounts are not removed and the periphery can be equipped with a gutter. A collecting device is shown in Figs. 7, 8 and 9 which efficiently operates as the sole removing device but which can be used in conjunction with the others illustrated. During operation, plate 166 rotates in the direction indicated and material to be distilled is introduced through conduit 178 into reservoir 176. The liquid passes into the space 174 and is thrown as a film over the surface of 166 and into gutter 164. The distance between the plate edge and the gutter is small 45 and is so adjusted that little or no splashing takes place. During rotation, element 180 scrapes the liquid from the gutter and throws it into the conduit 170 which conveys it to any desired point.

In Figs. 10, 11 and 12, liquid from the revolving 50 plate is received in a gutter from which it is withdrawn by a suitably located conduit. In Fig. 10, the plate 202 is vertical and the liquid in the gutter is prevented from dropping out by turned edges 106. In Fig. 11, the plate is horizontal. 55 Splashing of liquid in the gutter is prevented by placing the slit at the top so that the plate is substantially out of contact with the body of liquid in the gutter. In Fig. 12 the shaft and plate assembly of Fig. 11 is mounted at an angle to increase the rate of flow of liquid in the gutter to the lowest point at which the withdrawal conduit is located.

During operation of the apparatus illustrated in Fig. 4, conduit 103 is connected to the high 65 vacuum pumps (not shown). Liquid to be distilled is introduced into distributing device 91 by way of conduit 111. The liquid is evenly distributed in the form of a thin film and flows down the walls of element 84 at the zone 87. This zone 70 is heated to a temperature appropriate for removing the desired fraction. Undistilled residue flows from the lowest point of element 84 into withdrawal conduit 83. Molecules vaporized from vaporizing zone 87 are condensed upon the 75

air-cooled walls of casing 80 between gutters 82 and 100. The condensate flows down the walls into the gutter 82 and is withdrawn therefrom by conduit 104 and pump 105 and delivered to distributing device 92 which evenly distributes it over the surface of zone 88 which is preferably heated to a lower temperature than zone 87. The liquid flows over the heated walls of 84 at zone 88 and vaporized constituents are condensed upon the walls of casing 80 in the area between gutters 100 and 101. Condensate flows down the walls into gutter 100 and is removed therefrom by conduit 106 and pump 107 and delivered onto distributing device 93. This liquid then flows over zone 89 heated to a somewhat lower temperature and vapors removed at that zone are collected in gutter 101 and delivered to distributing device 94 by way of conduit 108 and pump 109. The liquid then flows over zone 90, heated to a still lower temperature where a final fraction is distilled which is collected in gutter 102 and is removed from the still by way of conduit 110.

In Fig. 5, distilland is introduced onto the top 25 of vaporizing segment 90'. Undistilled residue flows to the horizontal portion at the base thereof where it collects and is redistributed onto the next segment 89' and so forth. This construction results in more efficient distribution of distilland, as 30 a thin film onto the vaporizing surfaces, and also has the advantage of increasing the clearance for removal of gas through conduit 103'.

It will be apparent that the apparatus illustrated in the various figures can be considerably 35 modified without departing from the spirit or scope of my invention. For instance, the number of vaporizing and condensing zones or plates can be varied greatly to suit the particular substance in question or degree of fractionation required. It is preferable to have the zones progressively decrease in area and according to some geometric ratio, such as $\frac{1}{2}$; $\frac{1}{4}$; $\frac{1}{8}$ or 1; $\frac{1}{3}$; $\frac{1}{6}$, etc. Otherwise, considerable difficulty and inconvenience is encountered in trying to regulate the successive zones so as to give only the required extent 45 of distillation. Complete distillation on each zone might result in the absence of careful and constant control and no fractionation would, therefore, take place. The scoops for removing the liquid from the centrifugal surface can be constructed in a variety of forms other than those illustrated. It will be apparent that the scoop of Fig. 3 will vary in width according to the speed of rotation and that it should be as wide as the 50 distance of travel of the liquid for each rotation. Otherwise, two or more scoops should be employed. When vertical rotating plates are used, such as used in Figure 10, the scoop should be located at the top of the plate, since the liquid removed can then flow by gravity to any point 55 in the still. In this manner, the centrifugal plates are caused to also act as pumps. It is of course satisfactory to employ a stationary condensing surface in conjunction with a centrifugal 60 vaporizing surface. Such apparatus could easily be constructed similar to that of Fig. 1 wherein the plates are vertical, the only change being to mount the condensing plates in a stationary manner and place a collecting gutter at their lower 65 edges. The condensate would then flow into these gutters by gravity. Instead of a separate body of cooling liquid for each plate, a single stream can be circulated in series over the plates. This liquid must obviously have a low vapor pressure 70 at the temperature of distillation.

When separating a particular fraction, some of the volatile constituents which should have been first removed are still coming over, some of the heavier constituents which should wait until later have started to come over and some of the desired components which should be distilled, fail to do so because they have gone to the wrong fractions. Accordingly, to obtain all of any one constituent, a very much larger fraction must be secured as a first fraction. On a second distillation, the desired constituent can be concentrated further by distilling a large portion of the first fraction, the amount distilled being necessarily less than in the first step. This is more or less automatically controlled by varying the sizes of 10 the plates as previously explained. The size of the fractions and the plates may vary according to various geometric decrements of which diminution by halving is probably the most useful. It is obvious that with such repeated distillations, 15 thermal decomposition will be great and it is for this reason that the centrifugal apparatus is of such value for this purpose.

It will be apparent that the apparatus of Fig. 1 20 can be employed with several similar units in series, or that each pair of condensing and evaporating centrifugal plates can be a separate unit. Also, other obvious methods of recycling or mixing in order to concentrate a particular fraction 25 can be practiced. For instance, if it is desired to concentrate a heavy fraction instead of a light one, the material to be distilled is passed successively over a series of evaporating plates at successively higher temperatures, distillate from each 30 section is passed in a reverse direction, or to the next lowest temperature evaporating plate and the desired heavy fraction is withdrawn at one of the higher temperature plates after the removal of components of low volatility is substantially 35 complete. The centrifugal plates are rotated at 40 a speed such as to give the desired heating period. Speeds of between 250 and 30,000 R. P. M. will most generally be employed.

The invention permits an unlimited degree of 45 fractionation, depending only upon the units employed. In order to increase the utility of such a fractionating still, it can be employed in connection with a reservoir for residue which can be recycled through or over the still surfaces. After all of one fraction has been recovered by continued recycling, the temperatures of the units 50 can be adjusted for removal of a second fraction and the contents of the reservoir again recirculated through the still until all of that fraction has been recovered. Such operation permits one 55 still to separate an unlimited number of components and to fractionate each component to a degree corresponding to the number of temperature or distilling zones in the still. The use of such a reservoir and the principles of recycling are 60 more fully disclosed in my copending application No. 75,163, filed April 18, 1936.

The invention is applicable to high vacuum, distillation processes in general and particularly those in which the vaporizing and condensing 65 plates are separated by unconstricted space. Such processes are well known in the art. It is advantageous in most distillations to have the condensing and evaporating surfaces separated by rather short distances usually of less than about 70 1 foot. When distilling under molecular conditions, this distance is less than about the mean free path and usually about $\frac{1}{2}$ to 6 inches.

The pressure of residual gas in the space between the surfaces should be maintained at a suit- 75

able low value. When distilling under molecular conditions, the pressure should be about .1 mm. or less and preferably less than about .01 mm. such as .005 to .001 mm. I also contemplate employing high saturation distillation, such as described in my copending application No. 174,491, filed November 3, 1937. When operating in this manner, the vaporizing surface is maintained at a temperature sufficiently high to give a vapor stream of the distillate having a pressure of less than about 1 mm. of mercury, but of such density that the molecules of vapor travel more than five times their mean free path in passing to the condensing surface, and the pressure of residual gas is maintained lower than the pressure of the distilling molecules between the two surfaces.

It is evident that my invention is not limited to the treatment of particular materials and that it is of general use for distilling organic substances which are distillable under high vacuum distillation conditions. Examples are the recovery of low or intermediate fractions from high boiling hydrocarbons and the distillation of animal and vegetable oils such as linseed, soy bean, cod liver, etc. oils to recover unsaturated glycerides, sterols or vitamin fractions.

In addition to the many advantages pointed out above, the apparatus of Fig. 1 has the distinct advantage that pumps for circulating fractions or cooling fluid are not required. The apparatus of Fig. 4 has the advantage that only distillate must be pumped. Both types are furthermore compact and easy to regulate and operate by a single set of controlling operations. The gravity column is excellent for most substances but with extremely thermal sensitive compounds the repeated and prolonged heating under gravity flow conditions causes more or less decomposition. Due to the rapid heating in the centrifugal still of Fig. 1 such substances can be fractionated and refractionated without loss. It is to be noted that this is a result which has long been desired but which heretofore has not been possible.

45 What I claim is:

1. Apparatus for the separation of constituents of a mixture distillable under high vacuum, unobstructed path conditions which comprises in combination a series of pairs of closely adjacent 50 rotatable surfaces, one of each pair being provided with a heater and adapted to serve as an evaporating surface and the other of each pair being adapted to be cooled and serve as a condensing surface, means for conveying condensate onto the evaporating surfaces in succession, and means for conveying undistilled residue onto the evaporating surfaces in reverse succession.

2. Apparatus for the separation of constituents of a mixture which is distillable under high vacuum, short path conditions, which comprises in combination a series of pairs of rotatable surfaces, one of each pair being provided with a heater and adapted to serve as an evaporating surface and the other of each pair being provided with cooling means and adapted to serve as a condensing surface, means for maintaining a high vacuum between each pair of surfaces, means for collecting undistilled residue from each evaporating surface except the last of the series 65 and passing it in succession over each evaporating surface of the series, a conduit for withdrawing undistilled residue from the last evaporating surface of the series, means for collecting condensate from each condensing surface and pass-

ing it in succession over the evaporating surfaces of the series, but in an opposite direction to that in which undistilled residue is passed, means for introducing material to be distilled onto one of the evaporating surfaces and means for withdrawing a final distillate from at least one plate which is remote in the series from the evaporating surface upon which the material to be distilled is introduced.

3. Apparatus for the separation of constituents of a mixture which is distillable under molecular distillation conditions which comprises in combination a series of closely adjacent pairs of rotatable surfaces, one of each pair being provided with a heater and adapted to serve as an evaporating surface and the other of each pair being provided with cooling means and adapted to serve as a condensing surface, means for maintaining a high vacuum between each pair of surfaces, a conduit for introducing material to be distilled onto the first of the series of evaporating surfaces, means for conveying condensate from each condensing surface, except the last to the evaporating surface of the next pair of the series, means for conveying undistilled residue from each evaporating plate, except the first, to the next evaporating plate of the series, but in a succession reverse to that in which condensate is passed, means for removing undistilled residue from the first evaporating plate and means for removing distillate from the last condensing plate.

4. Apparatus for the separation of constituents of a mixture distillable under high vacuum, short path distillation conditions which comprises in combination a series of closely adjacent pairs of rotatable surfaces, one of each pair being provided with a heater and adapted to serve as an evaporating surface, these surfaces progressively decreasing in size from one end of the series to the other and the other surface of each pair being provided with cooling means and adapted to serve as a condensing surface, means for maintaining a high vacuum between each pair of surfaces, a conduit for introducing material to be distilled onto the first and largest of the series of evaporating plates, means for withdrawing undistilled residue from this plate, means for conveying condensate from each condensing surface, except the last, to the next smallest evaporating surface of the next pair of plates, means for conveying undistilled residue from each evaporating plate to the next largest of the evaporating plates and means for collecting and withdrawing condensate from the condensing surface opposite the last and smallest evaporating surface.

5. Apparatus for the separation of constituents of a mixture distillable under high vacuum, short path distillation conditions which comprises in combination a series of pairs of closely adjacent rotatable surfaces, one of each pair being provided with a heater and adapted to serve as an evaporating surface and the other of each pair being adapted to be cooled and serve as a condensing surface, conduits for conveying condensate onto the evaporating surfaces in succession and means for conveying undistilled residue onto the evaporating surfaces in reverse succession, the evaporating surfaces progressively decreasing in surface area according to a geometric ratio and in the same order as that in which condensate is passed thereover.

KENNETH C. D. HICKMAN.
